INHALER

Victor C. Hall, Media, Pa., assignor to Sharp & Dohme, Incorporated, Philadelphia, Pa., a corporation of Maryland

Application April 9, 1949, Serial No. 86,522

6 Claims. (Cl. 128—206)

1

This invention relates to inhalers and more particularly to an article of this character for use in inhaling powdered therapeutic material through the nose or through the mouth.

Certain diseases of the respiratory tract are known to respond to treatment by the direct application of designated therapeutic agents. As these agents are most readily available in dry powdered form, their application is most conveniently accomplished by inhaling the powdered material through the nose or mouth.

If the disease tissue is in the nose, the powdered material is best drawn up into the nasal cavity. If the afflicted tissue is in the lower tract, as in the lungs, the powdered therapeutic agent is conveniently inhaled through the mouth. The inhaler should be useable in both instances.

As the inhalation of the powdered material will, in any event, bring it into the throat area, a coughing reaction will be brought about unless the powder is finely dispersed into the air stream being inhaled. As the throat membranes are already likely to be in irritated condition arising from the need for a curative treatment, a concentrated application will further aggravate the condition.

It is therefore important that the inhaler serve to deliver the powdered material into the inhaled air stream over a prolonged period and to make certain that a large amount of the material cannot become dislodged into the air stream at any moment. These results are obtained with the inhaler of the present invention. Due to its novel features of construction, only a regulated, small amount of the powder can be delivered into the air stream being drawn through the inhaler.

Inasmuch as the therapeutic material is likely to be expensive, it is important that none of it be spilled or otherwise be lost from the inhaler. The construction of the present inhaler makes it practically impossible to waste the agent from the inhaler and assures delivery of the entire charge into the air stream and to the patient.

Another important feature of the article of the present invention is that it makes it possible to use conventional capsules in which the powdered material is commercially supplied. As these capsules are obtainable at the lowest cost, their direct use as a part of the inhaler of the invention, materially contributes to the ease of use of the inhaler.

A preferred embodiment of the invention is disclosed in the accompanying drawings, in which:

Fig. 1 is a side elevational view;

2

Fig. 2 is an exploded view, a portion of the base being broken away to show the action of the capsule piercing instrument;

Fig. 3 is an elevational view in vertical section;

Fig. 4 is a sectional view on the line 4—4 of Fig. 3; and

Fig. 5 is a side view of the capsule piercing instrument.

Generally considered, the inhaler consists of an outer hollow body or shell 10 and an inner powder containing capsule 11. It may be observed at this point that the capsule 11 is of the conventional type consisting of two telescopic sections. The body of this capsule is preferably made of the usual frangible, relatively rigid, plastic material.

To most easily enable the disposition of the capsule 11 within the hollow interior of the shell 10, the shell is made in two separable portions. These include the base 12 and the cover 13.

The base 12 has a lower flange 14 and an upper cylindrical extension 15. The flange 14 presents an upwardly facing seating surface 16 and the cylindrical extension 15 presents an upwardly facing seating surface 17. These surfaces 16 and 17 coact with the cover 13 to form an air tight seal, as will later appear.

Within the top of the base is a recess 18 to receive the capsule 11. As here shown, the recess 18 is of elongated shape to conform to the general contour of the capsule 11. It is preferable that the recess 18 be slightly deeper than the capsule so that during the time that the capsule is being held downwardly into the recess under manual pressure, it will not be easily dislodged. This is desirable while the capsule is being punctured, as will be explained.

Through the wall of the cylindrical extension 15 are openings 20. It will be observed that these openings 20 are in axial alignment with each other and with the axis of the capsule recess 18. As a consequence, the openings 20 enter into the opposite ends of the capsule recess 18.

These openings 20 serve as guideways for the insertion of an instrument 21 for piercing the ends of the capsule 11. This instrument is generally of rod or pin-like shape. One end of the shaft of this instrument 21 is preferably enlarged to form a head or finger gripping portion 22 and the other end is preferably pointed, as at 23, to enter the end of the capsule 11.

It has been advisable to provide means for limiting the insertion of the piercing instrument 21. This may be accomplished by having its shaft portion of such length that the head 22 will strike against the body of the base 12 when the

pointed end 23 has sufficiently entered the capsule 11. However, for ease of use, it has been found preferable to form a shoulder at 24 on the shaft of the instrument, and a shoulder at 25 within the openings 20, which will contact at the desired limit of insertion.

The shoulder 24 on the shaft of the piercing instrument 21 is most easily formed by reducing the size of the shaft at the desired point, to the piercing end 23 thereof. To form the shoulder 25 within the openings 20, these openings are merely shaped with counterbores from the periphery of the base.

The cover 13 is of cylindrical shape at its lower portion and has a rounded or dome shaped top 26. A hole 27 is formed through this top. This rounded shape of the top 26 is so that it may be easily pressed against a nostril opening, or against the lips so that it can be drawn upon during inhaling. The top can, of course, be made of more pointed or conical shape, if desired, to suit personal preferences.

The open end of the cylindrical portion of the cover 13 frictionally fits upon the cylindrical extension 15 of the base 12. The end face 28 of the cover 13 bears against the seating surface 16 to further make an air-tight seal. Within the open end of the cover 13 is formed a shoulder 29 to bear against the seating surface 17 of the base, to make an even tighter seal. Either one of these abutting seating surfaces is sufficient, if it is desired to simplify the construction, but one pair of seating surfaces is desirable to limit the insertion of the base within the cover.

The chamber 31 within the cover 13 is larger in all dimensions than the greatest dimension of the capsule 11. This relationship is important so that the capsule 11 can turn about in all directions within the chamber 31 as it is agitated by the flowing air stream.

To permit entrance of air into the hollow interior of the inhaler shell, ports 32 are formed through the side wall of the cover 13. It will be observed that these ports 32 pass angularly through the cylindrical wall of the cover 13 so that the entering air is delivered generally tangentially into the chamber 31. This causes a circular, whirlpooling motion of air within the chamber 31.

The top of the agitation chamber 31 is defined by a screen 33. It may be held in place in any suitable manner. As here shown, it is cemented against an internal annular surface 34 of the cover 13. This screen 33 serves to keep the capsule 11 within the large chamber 31 so that it can move about more freely than it could if it were to enter up into the smaller dome shaped top of the cover 13. It keeps the capsule away from the hole 27 and thus overcomes any tendency to block flow of air and powder therethrough. Also, the screen 33 is of fine mesh to hold back any large powder particles and any broken fragments of the perforated capsule.

The shell is preferably made of a clear plastic as polystyrene or an acrylic copolymer, but it can be made of any synthetic or metallic material. For example, it can be made of a phenol-formaldehyde resin or of aluminum. The puncturing instrument is preferably made of some metal as aluminum or stainless steel, but it can as well be made of a hard plastic.

In using the inhaler, the shell is separated and the capsule 11 is placed in its recess 18. While holding the capsule in place with the fingers, the piercing instrument 21 is passed into the guide-way openings 20 so that the pointed end of the in-

strument pierces the end of the capsule. The instrument 21 is then withdrawn from that particular guide opening and inserted into the opposite guide opening to pierce the other end.

The cover 13 is then placed upon the base 12. It will be noted that the lower end of the cover 13 closes the ends of the guide openings 20 and thereby prevents escape of the powdered material out of these openings.

When the top end of the inhaler is then drawn upon, either through the nose or through the mouth, air is drawn into the tangential ports 32. The resulting swirling or whirlpooling motion of this air above the capsule serves to lift the capsule out of the recess 18 and to bring it up into the chamber 31. Within the chamber 31 the capsule turns about in all directions and serves to dislodge or eject the contained powder out of its open ends. As the motion of the capsule is primarily one of rotation about a vertical axis which is transverse to the length of the capsule, the resulting centrifugal action ejects the powdered material out of the opposite ends of the capsule.

This action of dislodging the powdered material into the air stream continues during the entire time that suction is applied to the top end of the inhaler. Inasmuch as the powder can escape only through the small openings which have been formed in the ends of the capsule, the delivery of the powdered material is at a reduced rate and it is impossible for a large sudden discharge to be administered.

After such use, the inhaler is separated and the capsule is removed and thrown away. It will be observed that there is no loss, therefore, of any expensive portion of the article. The piercing instrument is then placed within the chamber 31 so that it will be retained with the article during the time that the article is not in use.

It will be observed that the size of the holes which are formed in the opposite ends of the capsule 11 will determine the rate of delivery of the powdered material from the capsule. As a consequence, by employing a piercing instrument having a larger diameterd punching end, larger holes will be formed in the capsule and consequently the powdered material will be delivered in a greater quantity. This may be desirable with powdered materials that do not flow freely out of a small opening. Conversely, the penetrating instrument can be formed with a smaller pointed end so that smaller holes will be formed in the capsule if a slower rate of discharge is desired.

What is claimed is:

1. An inhaler for medicinal powder comprising a body having a cavity therein and also having openings from the cavity to the exterior of the body at displaced points whereby a suction applied at one of the openings will cause air to flow into the other opening and sweep through said cavity, positioning means for initially holding a container of powdered material in place within said cavity, guide means for directing a piercing instrument against the container while being restrained by said positioning means so that the container can be punctured, whereby the air current sweeping through the cavity will agitate the container and dislodge its contents through the punctured opening into the air current.

2. An inhaler for medicinal powder comprising a body having a cavity therein and also having openings from the cavity to the exterior of the body at displaced points whereby a suction applied at one of the openings will cause air to flow

into the other opening and sweep through said cavity, positioning means defined by the wall of a recess internally of said body for initially holding the container of powdered material in place within said cavity, guide means defined by an opening through the wall of said body for directing a piercing instrument against the container while being restrained by said positioning means so that the container can be punctured, whereby the air current sweeping through the cavity will agitate the container and dislodge its contents through the punctured opening into the air current.

3. An inhaler for medicinal powder comprising a body having a cavity therein and also having openings from the cavity to the exterior of the body at displaced points whereby a suction applied at one of the openings will cause air to flow into the other opening and sweep through said cavity, a container for the medicinal powder located within said cavity, guide means for directing a piercing instrument against the container while positioned in the cavity to puncture it, the cavity in said body being larger in all dimensions than the container, whereby the punctured container can become agitated and turn about in all directions and dislodge its contents into the air current sweeping through the cavity.

4. An inhaler for medicinal powder comprising a body having a cavity therein and also having openings from the cavity to the exterior of the body at displaced points whereby a suction applied at one of the openings will cause air to flow into the other opening and sweep through said cavity, a container for the medicinal powder located within said cavity, positioning means for initially holding the container in place within said cavity, guide means for directing a piercing instrument against the container while being restrained by said positioning means so that the container can be punctured, the cavity in said body being larger in all dimensions than the container, whereby the container can become agitated and turn about in all directions and dis-

lodge its contents into the air current sweeping through the cavity.

5. An inhaler for medicinal powder comprising a body having a cavity therein and also having openings from the cavity to the exterior of the body at displaced points whereby a suction applied at one of the openings will cause air to flow into the other opening and sweep through said cavity, and a container for the medicinal powder located within said cavity, the internal wall of said body having a recess therein for initially holding the container in place within said cavity, the wall of said body having an opening therethrough entering into said recess for directing a piercing instrument against the container while being disposed in said recess so that the container can be punctured, the cavity in said body being larger in all dimensions than the container, whereby the container can become agitated and turn about in all directions and dislodge its contents into the air current sweeping through the cavity.

6. An inhaler for medicinal powder comprising a body which includes a base and a hollow cover, means on the base and cover for their interfit to retain them in assembled relationship, said base having a recess therein to receive a container for powdered material, the wall of said base having an opening therethrough entering into said recess for guiding a piercing instrument against the container in the recess so it can be punctured, said cover having an outlet opening to be drawn upon, and said body having an inlet opening therein at a displaced point so that when suction is applied to the outlet opening a current of air will sweep through the hollow interior.
